CLAIM

The ornamental design for a mounting bracket for a heat sink module, as shown and described.

DESCRIPTION

FIG. 1 is top perspective view of a mounting bracket for a heat sink module;

FIG. 2 is a bottom perspective view of the mounting bracket of FIG. 1;

FIG. 3 is a top view of the mounting bracket of FIG. 1;

FIG. 4 is a bottom view of the mounting bracket of FIG. 1;

FIG. 5 is a front view of the mounting bracket of FIG. 1;

FIG. 6 is a rear view of the mounting bracket of FIG. 1;

FIG. 7 is a left side view of the mounting bracket of FIG. 1;

FIG. 8 is a right side view of the mounting bracket of FIG. 1;

FIG. 9 is a top perspective view of the mounting bracket of FIG. 1; and,

FIG. 10 is a top view of the mounting bracket of FIG. 1.

The broken lines shown in the figures are for illustrative purposes only and form no part of the claimed design.
